UNITED STATES PATENT OFFICE.

RAYMOND R. WALKER, OF FOLLANSBEE, WEST VIRGINIA.

BOTTLE WASHER.

1,408,848.

Specification of Letters Patent.

Patented Mar. 7, 1922.

Application filed January 27, 1921. Serial No. 440,548.

To all whom it may concern:

Be it known that I, RAYMOND R. WALKER, a citizen of the United States of America, and resident of Follansbee, county of Brooke, 5 and State of West Virginia, have invented certain new and useful Improvements in Bottle Washers, of which the following is a specification.

This invention relates to bottle washers, 10 and it has for its primary aim and object to provide a simple and efficient device designed for attachment to an ordinary water faucet for the washing of bottles, tumblers and like articles.

15 The invention resides in the embodiment of a fluid motor in the washer for driving a rotary brush, said motor being arranged in the flow of the cleansing fluid for being actuated thereby.

20 Further, the invention resides in an improved fluid control operable by the bottle when properly disposed on the washer.

The invention resides in the features of construction, arrangement of parts and combinations of elements which will hereinafter be fully described, reference being had to the accompanying drawings, in which—

Figure 1 is a front elevation of the invention depicted as attached to an ordinary 30 faucet;

Figure 2 is a vertical section therethrough on line 2—2, Figure 1, showing the working parts of the washer;

Figure 3 is a horizontal section on the line 35 3—3, Figure 2; and—

Figure 4 is a vertical fragmentary section, showing the tumbler rest or support in its operative position.

Referring to the drawings, the washer 40 mechanism is depicted as mounted on one arm of a substantially U-shaped pipe 1, the other arm of which is provided with a coupling 2 for ready attachment to an ordinary water faucet 3. A valve 4 is carried by the 45 outer arm of said pipe 1 and is connected by a short length of pipe with the interior of the fluid motor casing 5. This casing is of cylindrical form and divided intermediate its ends to provide upper and lower sections 50 that have threaded connection with each other, as indicated at 6. The lower casing section is interiorly threaded to securely receive a disk 7 which is provided with an annular series of perforations 8 adjacent to its periphery and which constitutes a support for a rotor 9, a ball 10 being preferably

interposed axially between the latter and the disk, and constituting a bearing for the rotor. A vertical shaft 11 is fixed on the rotor and extends axially therefrom through the upper casing section, said shaft being adapted to carry a brush 13 upon its upper end. Located in concentric embracing relation to the shaft 11 is a fluid delivery pipe 12 mounted at its lower end upon a thrust bearing 14 seated upon ball bearings 15 interposed between it and the rotor.

The rotor is formed with inclined peripheral grooves through which the water passes from the perforations 8 of the disk 7 for imparting rotary motion to the rotor and the vertical shaft 11. A disk 16 is threaded into the lower casing section above the rotor to relieve the latter of back pressure, said disk having perforations 17 which closely 75 overlie said rotor and provide outlets for the passage of the water. A set screw 18 directed through a collar on the upper casing section impinges upon the pipe 12 to hold the latter and the casing in fixed relation. The water or other washing fluid enters the delivery tube 12 through lateral ports 19 which open into the upper casing section, and is delivered from the upper end of the tube through ports 20 which are 80 preferably designed to provide a whirling spray. The discharge of the washing fluid is directly beneath the brush 13 so that the latter is constantly supplied with fresh clean 85 fluid.

A funnel 21 slidable upon the pipe 12 is yieldably supported by a coil spring 23 which rests upon an adjustable collar 22 that is held in adjusted position on the pipe by means of a set screw 24. The funnel is 95 provided with a flanged seat 25 which seats upon said spring, and carried by said funnel is a drain or outlet 26 through which the waste water may flow into a sink or other waste receptacle. The funnel carries a fixed 100 cross arm 27 to which the substantially parallel members of an inverted U-shaped frame 28 are attached, the transverse upper bar of the frame embodying a central loop 29 which encircles the delivery pipe 12 and constitutes a rest for the bottle, as indicated. One member of the frame 28 is extended 105 downward and is connected to a lever 30 carried by the valve 4 whereby, when the frame is depressed, the valve is opened 110 automatically.

In the practical operation of the washer, a

bottle, as depicted at 31, is slipped over the brush 13 to a position in which it seats upon the ring support 29. The weight of the bottle seated upon said support depresses the frame 28 against the tension of spring 23, resulting in the lever 30 being swung downward to valve opening position. As the fluid is permitted to flow through the casing 5 it acts upon the peripheral vanes of the 10 rotor and impels the same to rotate the shaft 11 and the brush 13. From the casing the water passes into the pipe 12 and thence travels upward and issues from the orifices 20 immediately beneath the brush in the 15 form of a whirling spray. This spray not only supplies the brush with clean fluid but effects a direct cleansing and rinsing action upon the inner walls of the bottle.

For the cleansing of tumblers and wide 20 mouth receptacles, a rubber funnel 32, Figure 4, is removably mounted upon the ring 29, the same having a flanged seat 33 to snugly receive the inverted tumbler. The brush in this instance is necessarily of a 25 somewhat different form adapted for the particular article. When this auxiliary funnel is employed the waste water passes through the axial depending spout about the delivery pipe and down into the main funnel 21 and thence out through the waste pipe 26.

The device is lightly and simply constructed, thereby adapting it for use on the ordinary faucet in a private home, the same being 35 compact so as to occupy little space. The fluid is automatically turned on as a bottle is inserted in position, and, since the water acts to operate the rotor, no independent means or manual operation is necessary to 40 impart a rotary movement to the brush. The term "bottle" is herein used to include tumblers and all open-mouth receptacles or containers.

What is claimed is—

45 1. A bottle washer comprising a casing, a water-actuated rotor within said casing, a valve connected to said casing, a shaft carried by said rotor, a fluid delivery pipe extending upwardly from said casing and

through which said shaft extends, a catch-receptacle slidable on the pipe, a collar adjustably fixed on the pipe, a spring interposed between the collar and receptacle for yieldably supporting the latter, a transversely disposed arm carried by the receptacle, a frame carried by said receptacle arm and embodying a loop encircling the fluid delivery pipe and adapted for supporting a bottle over the latter, and a connection between the valve and the frame whereby the former is opened and closed through lowering and elevating movements of the latter.

2. In a bottle washer, a rotor casing, a rotor therein, a shaft connected to the rotor, a fluid delivery pipe through which the shaft 65 extends, a brush mounted on the projecting end of the shaft, a catch receptacle slidable on the pipe and having a lateral discharge, a bottle supporting frame carried by said receptacle in overlying relation thereto, and a 70 valve for controlling the passage of fluid through the casing and having operative connection with the bottle supporting frame.

3. In a bottle washer, a rotor casing, a rotor therein, a shaft connected to the rotor, a fluid delivery pipe through which the shaft 75 extends, a brush mounted on the projecting end of the shaft, a catch receptacle slidable on the pipe, a bottle carrying frame slidable relative to the pipe and designed for supporting a bottle above the receptacle, a valve 80 for controlling the admission of fluid to the casing, and means connecting the frame to the valve for opening and closing the latter by and during movements of the frame.

4. In a bottle and tumbler washer a rotary brush, a bottle support embodying a circular seat located adjacent to said brush, and a tumbler support of funnel design insertible 90 in the seat and having a marginal annular flange overhanging the seat to receive and support a tumbler.

In testimony whereof, I affix my signature in presence of two subscribing witnesses.

RAYMOND R. WALKER
